United States Patent Office

Des. 186,355
Patented Oct. 20, 1959

186,355

SIPHON

Joseph B. Stier, New York, N.Y.

Application October 6, 1958, Serial No. 52,884

Term of patent 14 years

(Cl. D2—3)

Figure 1 is a front elevational view of a siphon showing my new design;

Figure 2 is a side elevational view; and

Figure 3 is a top plan view thereof.

I claim:

The ornamental design for a siphon, substantially as shown.
